UNITED STATES PATENT OFFICE.

JULIUS H. BECKER, OF SAN FRANCISCO, CALIFORNIA.

AUTOMATIC CUT-OUT MECHANISM FOR FLUID-ACTUATED DEVICES.

1,078,986.

Specification of Letters Patent.

Patented Nov. 18, 1913.

Application filed January 21, 1913. Serial No. 743,296.

To all whom it may concern:

Be it known that I, JULIUS H. BECKER, a citizen of the United States, residing in the city and county of San Francisco and State of California, have invented new and useful Improvements in Automatic Cut-Out Mechanism for Fluid-Actuated Devices, of which the following is a specification.

This invention relates to an automatic cut out mechanism for fluid actuated devices, which is particularly adapted for use in connection with hydraulic pumps.

The main object of this invention is to provide a simple, substantial and practical automatic controlling device which may be interposed between the main water supply and a hydraulic pump for the purpose of cutting off the supply once the pressure in the main has been reduced below a certain predetermined pressure; the device being so constructed that the automatic action of same may be controlled either by the primary pressure, or by the secondary pressure created by the hydraulic pump.

A further object of the invention is generally to improve this class of devices so as to increase their general applicability, utility and efficiency.

The invention consists of the parts and the construction and combination of parts as hereinafter more fully described and claimed, having reference to the accompanying drawings, in which—

Figure 1 is a side elevation showing the controlling device in the closed or cut-off position. Fig. 2 is a longitudinal section showing the controlling device in the open position. Fig. 3 shows the installation of the device on a straight pipe line.

The object of this invention is to provide an automatic pump controlling device which will act to entirely cut off the water under pressure supplied for operating hydraulic pumps when the pressure in the main falls below a predetermined pressure; this being of great importance when the following example is taken under consideration: Supposing that an oil pump delivering oil to a burner in a furnace is directly connected to a hydraulic pump, and that this is constructed to operate under a normal pressure of 60 pounds delivered from the water main. Now for some reason or other, the pressure in the main is considerably reduced, which might happen through such causes as the main being subjected to a heavy drain, caused by a fire

in the immediate vicinity, a bursted pipe, or like cause. A temporary reduction in pressure in the water main would naturally slow down the action of the pump or the number of reciprocal movements of same, and correspondingly reduce the quantity of oil fed to the burner, and in some instances it has happened that the oil supply is reduced to such small quantity as to temporarily extinguish the fire. If the normal pressure of the main should suddenly be restored, the hydraulic pump would immediately actuate the oil feeding pump, and the normal discharge would thus be supplied to the burner and discharged into the heated furnace. If the heat is sufficient within the furnace when a certain proportion of oil has been ejected, a sudden ignition would cause a violent explosion, while if the furnace had cooled down to a certain degree, the oil would simply be injected into the furnace and flood the furnace and overflow into the surrounding quarters.

The object of this invention, as before stated, is to prevent an accident of this nature by providing an automatic cut out mechanism, which, when the pressure of the main is suddenly decreased, will act to entirely cut off the water supply to the hydraulic pump, and thus prevent the accidents previously described.

By referring to Fig. 1 of the drawings, A indicates the pressure main from which water is supplied through a pipe 2, which in turn is connected with the automatic controlling device generally indicated at B, before it enters the hydraulic pump, indicated at C.

D indicates an oil pump of any suitable construction, which is directly connected with the hydraulic pump through a piston rod 3; the oil pump being provided for the purpose of carrying or elevating oil from any suitable source to an oil burner, not here shown, delivering the oil to the burner through a pipe 4. Interposed on the pipe line 4, between the oil pump proper and the burner, is a T connection 5, connected by a nipple 6 with a head portion of a cylinder 7, in which is slidably mounted the piston 8 adjustably secured upon the upper end of a piston rod 9. Interposed between the lower cylinder head and the piston 8 is a coil spring 10, which is so positioned that it will force the piston up into the upper end of the cylinder 7 when the oil pressure actuating the opposite side of the

piston is reduced below a certain predetermined pressure, which pressure is regulated and controlled by regulating the pressure of the spring 10, which in turn is accomplished by adjusting the position of the piston 8 on the piston rod 9; oil being supplied to the upper end of the cylinder from the pipe line 4 through the connection 6.

11 indicates a second cylinder which is open at both ends through which the piston rod 9 extends, and upon which is mounted a pair of opposed or balanced pistons 12 and 13. Surrounding the open ended cylinder 11 is a casing 14 having an outlet opening 16 and an inlet opening 15; the inlet opening being connected by the pipe 2 to the main, as shown in Fig. 1, while the outlet opening 16 may be connected as shown to the inlet 17 of the hydraulic pump.

20 Supposing that the normal oil pressure in the pipe line 4, which supplies the burner, is 20 pounds, and this oil under pressure, being conveyed from the pipe 4 through the pipe 6 to the upper end of the cylinder 7, 25 will actuate the piston against the compression of the spring 10, and will under this normal pressure hold the piston in the depressed position shown in Fig. 2. The position of the opposed balanced pistons 12 and 30 13 in the cylinder 11 will then be in a position to allow the water under pressure to pass through the pipe 2, the cylinder 11, and through perforations 18 into an annular passage 19, from where it is conveyed to the 35 outlet 16 to the intake 17 on the hydraulic pump. The moment, however, that the pressure of the water main is reduced below the normal operating pressure, it can immediately be seen that the pressure in the upper 40 end of the cylinder 7 will be sufficiently reduced to allow the piston 8 to move into the position shown in Fig. 1. The movement of the piston 8 caused by the expansion of 45 the spring 10 by the corresponding reduction of pressure on the opposite side of the piston from the lower position shown in Fig. 2, to the position shown in Fig. 1, is immediately transmitted through the piston rod 9 to move the pistons 12 and 13 into such a 50 position that the water passage through the cylinder 11 is cut off as the lower piston 13 is moved above the perforation 18 in the cylinder, so as to prevent the flow of water through the cylinder. The sudden return 55 of normal pressure in the water main A would in no way affect the automatic controlling mechanism, as the pressure supplied to the cylinder 11 through the inlet 15 would be ineffective to actuate the position of the 60 pistons 12 and 13 on account of the opposed balancing action of these pistons. The hydraulic pump would thus remain inactive until the extinction of the fire would attract the attention of the operator, and can then 65 only be started again by the operator de-

pressing the piston rod 9 into the position shown in Fig. 2, to allow the free passage of the water through the cylinder 11, and it will be necessary for the operator to hold the piston rod in this position until the oil pressure in the pipe line 4 has been restored to the normal operating pressure, which being transmitted through the pipe 6, will be operable to hold the piston 8 in this depressed position against the pressure of the 70 spring 10; a suitable extension or hand-grip 20 being secured on the piston rod 9 between the upper cylinder 7 and the lower cylinder 11 for the purpose of temporarily depressing the piston 8.

80 By referring to Fig. 3 of the drawings it can be seen that the device may be installed on any fluid pressure pipe line, and will be just as effective to cut off the flow through the pipe line when connected with the primary pressure as by the pipe 22. The reduction of pressure in the pipe line would be transmitted through the pipe 22 to the upper end of the cylinder and allow the spring to move the piston a sufficient distance to cut off the flow through the pipe line.

85 The automatic cut out mechanism here shown is simple and substantial in construction, and always positive in its action, and takes no more space than similar devices. The materials and finish of the several parts of the device are such as experience and judgment of the manufacturer may dictate.

90 I wish it understood that various changes 100 in form and proportions of construction may be resorted to within the scope of the appended claims and that I do not wish to limit myself to the specific design here shown.

105 Having thus described my invention, what I claim and desire to secure by Letters Patent, is—

110 1. An automatically-operated cut-off valve for fluid conveying pipe lines, comprising an open-ended cylinder interposed on the pipe line, inlet and outlet openings formed in the open-ended cylinder connecting the pipe line with the interior of the open-ended cylinder, a pressure cylinder disposed in 115 line with the open-ended cylinder, a piston in said pressure cylinder actuated by a spring on one side and by pressure conveyed from the discharge side of the open-ended cylinder on the other side, a piston rod extending from said piston through the open-ended cylinder, a piston secured to said rod at a point above the intake in the open-ended cylinder, and a piston secured to the rod at a point below the discharge opening formed 120 in the open-ended cylinder.

125 2. An automatic cut out mechanism for fluid actuated apparatus comprising in combination a fluid pressure pipe line, an open ended cylinder interposed in said pipe line, 130

a piston rod reciprocably mounted in the open cylinder, a pair of balanced pistons mounted upon the rod within the cylinder, inlet and outlet openings connecting the pipe line with the interior of the cylinder, an actuating cylinder supported above the open ended cylinder into which the piston rod projects, a piston secured on the end of the rod, means for conveying fluid pressure from the discharge side of the open ended cylinder to the upper end of the cylinder, and a coil spring interposed between the lower end of the cylinder and the piston.

3. An automatic cut-off mechanism for fluid-actuated apparatus, comprising in combination a cylinder, a piston slidably mounted in said cylinder, a pressure chamber formed in the cylinder on one side of said piston, a coil spring interposed between the lower end of the cylinder and the other side of the piston, a piston rod secured to said piston projecting through the lower end of the cylinder, a secondary open-ended cylinder mounted below the first-named cylinder through which the piston rod projects, inlet and outlet openings formed in the open-ended cylinder connecting the interior of the cylinder with a source of fluid supply and a fluid-actuated mechanism, a piston secured to said rod at a point above the intake in the open-ended cylinder, a piston secured to the rod at a point below the discharge opening formed in the open-ended cylinder, and a pipe connecting the discharge side of the open-ended cylinder with the pressure chamber formed in the upper portion of the first-named cylinder.

4. An automatic cut-off mechanism for fluid-actuated apparatus, comprising in combination a cylinder, a piston slidably mounted in said cylinder, a pressure chamber formed in the cylinder on one side of said piston, a coil spring interposed between the lower end of the cylinder and the other side of the piston, means for adjusting the tension of the spring, a piston rod secured to said piston projecting through the lower end of the cylinder, a secondary open-ended cylinder mounted below the first-named cylinder through which the piston rod projects, inlet and outlet openings formed in the open-ended cylinder connecting the interior of the cylinder with a source of fluid supply and a fluid-actuated mechanism, a piston secured to said rod at a point above the intake in the open-ended cylinder, a piston secured to the rod at a point below the discharge opening formed in the open-ended cylinder, and a pipe connecting the discharge side of the open-ended cylinder with the pressure chamber formed in the upper portion of the first-named cylinder.

5. An automatic cut-off mechanism for

fluid-actuated apparatus, comprising in combination a cylinder, a piston slidably mounted in said cylinder, a pressure chamber formed in the cylinder on one side of said piston, a coil spring interposed between the lower end of the cylinder and the other side of the piston, means for adjusting the tension of the spring, a piston rod secured to said piston projecting through the lower end of the cylinder, a secondary open-ended cylinder mounted below the first-named cylinder through which the piston rod projects, a casing surrounding the cylinder having an annular passage formed in its lower end which communicates with the interior of the cylinder through a series of perforations formed in the cylinder, an inlet opening communicating with the interior of the cylinder and the source of fluid supply, an outlet opening connected by a pipe with the fluid-actuated mechanism and the annular passage in the casing, valve means on the piston rod controlling communication between said inlet and outlet, a pipe connecting said pipe with the pressure chamber formed in the upper portion of the first-named cylinder, and manually actuated means secured on the piston rod between the upper cylinder and the open-ended cylinder by which the rod may be reciprocated.

6. An automatic cut-off mechanism comprising the combination of a fluid pressure supply pipe, a valve cylinder having a lateral inlet to which the supply pipe is connected, said cylinder having a lateral outlet for fluid admitted from the supply pipe, a valve in the cylinder consisting of a piston rod carrying two spaced pistons separated a distance in excess of the distance between said inlet and outlet so that both the inlet and outlet may simultaneously open into the cylinder in the space between the pistons, and the rod and pistons having a limit of movement sufficient to move them to cut off communication between said inlet and outlet, means by which said pistons are normally positioned to cut off communication between said inlet and outlet, means controlled by the pressure in the supply pipe to maintain said pistons in position with the inlet and outlet in communication, and means whereby on a reduction of pressure in the supply pipe below a predetermined point the pistons are moved to interrupt communication between the inlet and outlet.

In testimony whereof I have hereunto set my hand in the presence of two subscribing witnesses.
